United States Patent Office.

MARTIN HILTZ, OF GLOUCESTER, MASSACHUSETTS.

Letters Patent No. 71,879, dated December 10, 1867.

IMPROVEMENT IN FISHING-LINE SWIVELS.

The Schedule referred to in these Letters Patent and making part of the same.

TO ALL PERSONS TO WHOM THESE PRESENTS SHALL COME:

Be it known that I, MARTIN HILTZ, of Gloucester, in the county of Essex, and State of Massachusetts, have invented a new and useful Improvement in Fishing-Line Swivels; and do hereby declare the same to be fully described in the following specification, and represented in the accompanying drawings, of which—

Figure 1 is a side elevation, and

Figures 2 and 3 longitudinal sections of my improved swivel.

The common swivels, as ordinarily constructed, and as used by fishermen, are very liable to become worn and broken, and when so are difficult of repair, or generally have to be discarded. My improved swivel is so constructed that the parts most liable to wear can be easily removed from the rest, and others substituted, thus rendering it unnecessary to detach the swivel from the spreader or hook-line supporter.

In the drawings, A denotes the base portion of the swivel, it being provided with a grooved extension, *aa*, by which it may be tied or secured to the spreader by means of cord wound around it, and the branches of the extension. The base part A extends into and is jointed to a furcated portion, B, the joint-pin going through the two being seen at *b*. The portion B is formed tubular, or with a hole, *c*, extending through it axially, such being for the reception of the shank of a screw-bolt or pin, D, which is passed up through the hole *c*, so that the head *d* of the bolt shall be within the fork of the part B. The upper portion C of the swivel is provided with a hole, *f*, to receive the shank of the bolt. Such part C turns on the bolt, and is made with a chamber, *e*, extending transversely through it, such chamber being to receive two nuts, *g h*, which are screwed upon the bolt, one serving as a check-nut for the other. Now, in case of breakage or wear of the bolt, it may be easily removed from the parts B C, and another substituted without rendering it necessary to abandon the parts A B C.

The swivel, constructed as above described, is preferable in several respects to the common swivel.

I claim the improved swivel, as made with the screw-bolt D and the nut-chamber *e*, arranged and combined, as explained, with the parts A B C, constructed and applied together as specified.

MARTIN HILTZ.
